GUARD RAIL ASSEMBLY FOR SCAFFOLDING

Robert E. Cameron, Ballwin, Mo., assignor to Automatic Devices, Incorporated, Maryland Heights, Mo.

Filed Dec. 11, 1974, Ser. No. 531,530

Term of patent 14 years

Int. Cl. D25—99

U.S. Cl. D54—1 A

FIG. 1

FIG. 2

FIG. 3

FIG. 1 is a perspective view of a guard rail assembly for scaffolding showing my new design;

FIG. 2 is an enlarged side elevational view thereof;

FIG. 3 is an enlarged front elevational view thereof.

I claim:

The ornamental design for a guard rail assembly for scaffolding, substantially as shown.
